UNITED STATES PATENT OFFICE.

HARVEY E. BROWN, OF ST. LOUIS, MISSOURI.

PROCESS OF MAKING WIRE FABRIC.

1,359,667.

Specification of Letters Patent. Patented Nov. 23, 1920.

Original application filed November 19, 1915, Serial No. 62,321. Patent No. 1,224,270, dated May 1, 1917.
Divided and this application filed January 31, 1917. Serial No. 145,635.

To all whom it may concern:

Be it known that I, HARVEY E. BROWN, a citizen of the United States, residing at St. Louis, and State of Missouri, have invented 5 certain new and useful Improvements in Processes of Making Wire Fabric, of which the following is a specification.

My invention relates to improvements in process of making wire fabric, and, although 10 capable of different uses, is particularly well suited for producing wire fabric such as is employed in the construction of spring bed bottoms.

The object of the invention is to provide 15 an improved process of the class described capable of being employed in the production of widely varying sizes and constructions of wire fabrics; to provide a process which may be efficiently employed by automatic machinery for constructing such fabrics; and, in general, to provide an improved process of the character referred to.

This is a divisional application, the subject-matter of which is described but not 25 claimed in the original application Serial No. 62,321, filed November 19, 1915, which has now resulted in U. S. Patent Number 1,224,270, issued May 1, 1917.

Illustrating a specific application of my 30 invention, I will now describe a fabric-making machine in which my improved process may be efficiently utilized, said machine being shown in the accompanying drawings, in which—

Figure 1 is a front elevation;

Fig. 2 is a view showing a portion of the fabric formed by the machine;

Fig. 3 is a side elevation, the belt wheel being removed;

Fig. 4 is an enlargement of a part of Fig. 3, showing a portion of the forming mechanism;

Fig. 5 is an enlarged front view of a portion of the machine;

Fig. 6 is a view of some of the parts shown in Fig. 5, the parts, however, being in a different position;

Fig. 7 is a central section through the main portion of the machine;

Fig. 8 is an enlarged view of a portion of the fabric-carrying drum;

Fig. 9 is a plan view partly in section;

Figs. 10 and 11 are views showing the mechanism for forming the loops on the 55 ends of the fabric members; and

Fig. 12 is an enlarged view of the mechanism for folding the two sides of the fabric members in parallel position.

Like marks of reference refer to similar parts in the several views of the drawings. 60

15 represents a base or pillar upon which the operating parts of the machine are supported. Surrounding this base or pillar 15 is a collar 16 carrying a guide 17 for guiding the fabric to and from the drum, as will be hereinafter described. Secured to the upper end of the pillar 15 is a casting 18 to which the drum 19 is secured by means of a bolt or stud 20, as shown in Fig. 7. The drum 19 is arranged to rotate freely on the 70 inner end of the bolt or stud 20. This stud carries an eccentric cam 21, which cam is prevented from turning by means of a key 22 (Fig. 7). The object of the cam 21 is to cause the forming members 23 to protrude 75 from the face of the drum at the upper part thereof, as shown in Figs. 3 and 7. Each of these forming members 23 is provided at one end with a stop 24 and, near its central part, with projections 25 (Fig. 8) which are 80 adapted to form bends in the central part of the sides of the fabric members, as will be hereinafter more fully described. The members 23 are maintained in contact with the eccentric cam 21 by means of a ring 26 concentric with the said cam. In order to hold 85 the loops of the formed fabric members against the stops 24, I provide the drum with a plurality of detents 27, each of which is provided with a pinion 28. These pinions 90 28 are engaged by racks 29 set into the surface of the drum and actuated by a cam track 30 supported by a bracket 31 and arranged in a groove 31' formed around the periphery of the drum near its inner end. 95 Arranged between the forming members 23 on the face of the drum are stops 32 and wire guides 33, as best shown in Fig. 8. Adjacent to the detents 27, the drum 19 is provided with a number of blocks 34 which are 100 adapted to receive the formed fabric members and, together with the detents 27, hold the same in proper position for their loops to receive wire to form a new fabric member. The drum 19 projects beyond these 105 blocks 34 a suitable distance to receive the amount of fabric it is desired to form in one piece. The drum, as best shown in Fig. 1, has its periphery formed into a number

of flat faces, each of which is equal to a width of one of the fabric members. In the present machine, fourteen of these faces are shown formed on the drum. The number, 5 however, may be varied without affecting the operation of the machine. The rear end of the drum 19 is provided with a ratchet 35 having teeth corresponding in number with the number of faces on the periphery 10 of the drum 19. The drum is fed forward by means of a pawl 36 engaging with the teeth of the ratchet 35. The pawl 36 is pivoted upon an arm 37 carried by a reciprocating bar 38 mounted in guides 39 carried on 15 the casting 18. The bar 38 is operated by means of an eccentric which will be herein-after described. Secured to the upper end of the casting 18 by means of a bolt 40 is a casting 41 adapted to carry the main operating parts of the machine. This casting 41 supports the frame 42 in which is mounted the main shaft 43 of the machine. Mounted on the end of the shaft 43 is a belt or drive wheel 44 to which power is supplied from 20 any suitable source. Also mounted on the shaft 43 is an eccentric 45 connected by means of a strap 46 with the upper end of the bar 38 hereinbefore referred to.

Carried by the casting 41 is a pair of studs 30 50 upon which is slidably mounted a block 51. The block 51 is connected by means of a link 52 to one end of a lever 53 which is pivoted at 54 to a lug 55 carried by the casting 41, as best shown in Figs. 7 and 9. The 35 opposite end of the lever 53 is provided with an anti-friction roll 56 adapted to coöperate with a cam 57 carried on the main shaft 43. In this manner, the block 51 is reciprocated on the studs 50 for a purpose which 40 will hereinafter be set forth. The outer ends of the studs 50 are connected by means of a yoke 58 having an inclined face 59 adapted to coöperate with a correspondingly shaped face on a vertical bar 60. This bar 45 60 is situated in a slot 61 in the block 51 and is held in sliding relation thereto by means of cross pieces 62. The lower end of the bar 60 is provided with laterally projecting portions 63 so that the bar as a whole 50 forms a T-shaped member. The inner face of the bar is provided adjacent to its lower edge with a groove 64, as best shown in Fig. 10. The object of this groove is to engage the wire of which the fabric member 55 is to be formed. Loosely mounted in the block 51 are a pair of shafts 65. These shafts are so mounted as to have a limited amount of vertical movement. Rigidly secured to the shafts 65 are wings 66, as 60 shown in detail in Fig. 12. These wings are adapted to fold the sides of the fabric member in parallel position. Secured to each of the wings 66 is a blade 67, the inner face of which is provided with a groove 68 for en-

gaging with the wire of which the fabric member is to be formed. Each of the blades 67 is also provided with a central opening 69, as best shown in Fig. 10. The upper ends of the shafts 65 are provided with pinions 70 which engage with rack bars 71 for 70 operating the blades. These rack bars are mounted in suitable guideways in the casting 41 and are provided with inwardly projecting blocks 72 adapted to be engaged by cams 73 carried on the shaft 43. In order 75 to return each of the rack bars 71 to their normal position after being engaged by the cam 73, I provide a coil spring 74 which is secured at one end to a pin 75 carried by each of the studs 50 and at the other to a pin 80 76 carried by each of the rack bars 71.

Arranged outside of the studs 50 are a second pair of studs 80 also carried by the casting 41. Each of these studs 80 has pivoted on it a plate 81 having journaled in 85 its lower part a rock shaft 82. On the inner end of this rock shaft 82 is a forming pin 83, as best shown in Figs. 10 and 11. The plate 81 has secured to it, adjacent to the rock shaft 82, a blade 84 (Fig. 10) which 90 is adapted to coöperate with a cutting projection 85 on the rock shaft 82 in order to sever the wire. The cutting projection 85 not only coöperates with the blade 84 to sever the wire, but also forms a loop on the 95 same, as best shown in Fig. 11. A stop pin 86 is carried in each of the plates 81 to assist in the formation of the loop.

In order to rotate the shafts 82, each of said shafts is provided at its forward end 100 with a gear wheel 87, as shown in Fig. 5. These gear wheels 87 coöperate with rack bars 88 mounted in guides 89 carried on the plates 81. The upper end of each of the rack bars 88 is pivoted to a link 90, the 105 opposite end of which is pivoted to a lever 91. The lever 91 is in turn pivoted at 92 to a bracket 93 carried by the frame 42 and provided with an anti-friction roll 94 adapted to be engaged by a cam 95 on the main 110 shaft 43. In order to return the lever 91 to its normal position after it is operated by the cam 95, I secure to said lever one end of a spring 96, the other end of which is secured to the plate 81, as shown in Figs. 115 3 and 4. This spring not only serves to return the lever 91 to its normal position, but also normally holds the plate 81 against a stop 97 carried by a sleeve 98, rigidly secured to the stud 80. Secured to the upper 120 edges of the plate 81 are the ends of a U-shaped member 99 carrying wire guides 100, as best shown in Figs. 7 and 10. A wire guide 101 similar to the guides 100 is also carried on the plate 81 at the side opposite 125 to that into which the wire is fed. The member 99 is pivoted at point 102, as shown in Fig. 5, so that the said member will not

interfere with a slight rocking motion of the plate 81, which is caused by the formation of the loops on the end of the wire, as will be hereinafter described. In order 5 to feed the wire 103 into the machine, the wire is engaged by means of a feed dog of any usual construction. This feed dog 104 slides upon a rod 105, carried by a bracket 106 secured to the frame 42. The feed dog 10 is connected by means of a link 107 with an arm 108 having a slot 109 engaging with a pin 110 on a bevel gear wheel 111, carried on the frame 42, as best shown in Figs. 1 and 9. The arm 108 is pivoted to the frame 15 42 at 114. This bevel gear wheel 111 is engaged by a second bevel gear wheel 112 mounted on the end of the shaft 43. It will thus be evident that each time the shaft 20 43 is rotated, the feeding mechanism 104 will be reciprocated along the rod 105. Arranged on the rod 105, adjacent to the plate 15 81, is a detent 113 of any usual form for preventing the wire 103 from being moved backward during the return movement of 25 the feeding mechanism 104.

The operation of the machine will now be briefly described. The wire 103 is fed into the machine by the forward movement of the feeding device 104. The wire 103 first 30 passes between the blade 84 at the left hand side of the machine and its coöperating cutting projection 85. The wire then passes through the first wire guide 100 and through the loops of the fabric sections which have 35 been previously formed. After passing through the fabric sections, the wire then passes through the second guide 100 to the guide 101, and to the second cutting members 84 and 85. The stroke of the feeding 40 device is so arranged that slightly more wire will be fed into the machine than is necessary to form one of the fabric members. The surplus wire is cut off by the second cutting members 84 and 85, as shown 45 in Fig. 10. The purpose of this is to insure uniform length of the wire, even if there should be a slight variation of the feed. While the wire is fed through the loops of the preceding fabric members, the said loops 50 are held in alinement against the forming members 24 by means of the detents 27, as best shown in Fig. 8. After the wire has been fed into position, as shown in Fig. 10, the cams 95 will come into contact with the 55 anti-friction rolls 94 on the levers 91 and actuate the said levers to raise the rack bars 88, and thus rotate the rock shafts 82 so as to cause the members 85 to coöperate with the blades 84 in cutting the wire at both 60 ends, and to also cause said members to carry the ends of the wire around the loops forming pins 83, so as to form loops 115 on the ends of the wire 103, as best shown in Fig. 11. It will be evident that the formation of these loops on the ends of the wire 65 will somewhat shorten the wire. This is compensated for by the movement of the plates 81 toward each other on their pivots. After the formation of the loops 115 on the ends of the wire 103, the cam 57 comes in 70 contact with the anti-friction roll 56 on the end of the lever 53, thus causing the block 51 to be moved rearwardly along the studs 50. This movement of the block 51 along the studs 50 allows the member 60 to move 75 downwardly and as this member supports the wings 66, the said wings also move downwardly, so that said parts assume a position such that the grooves 64 and 68 in the members 63 and 67 will engage with the 80 wire 103. The arms 63 of the member 60 hold the central part of the cross piece of the fabric member against the stop pin 32 while the blades 67 fold the sides of the fabric member into position. The object of 85 raising the member 60 and wings 66 on their rearward movement is to remove them out of the path of the various projecting portions of the drum 19. After the loops 115 have been formed upon the ends of the 90 wires, the cams 73 come into contact with the blocks 72 on the rack shaft bars 71, thus actuating the pinions 70 to rotate the shafts 65 and thus fold the wings 66, as best shown in Fig. 12. This folding of the wings 66 95 causes the blades 67 to engage with the wire 103 and bend the same around the forming members 24, so as to form parallel side pieces 116 of the fabric members. Half loops 117 are thus formed at two corners of 100 the fabric member. At the same time, the sides 116 of the fabric member are folded into parallel position, the recesses 69 in the blades 67 coöperate with the projections 25 on forming members 24 to form bends 118 in the side members 116, and thus increase 105 their resiliency. After the cams 73 release the rack bars 72, they are returned to their normal position by means of the springs 74 and the parts of the machine thus assume 110 their normal position. The drum 19 is now fed forward by the action of the feed pawl 36 and the machine is ready to begin the operation of forming a new fabric member. 115

The formed fabric members, after leaving the drum 19, are engaged by the guide 17, and are carried downwardly and then upwardly, at the opposite side of the drum where they are again delivered to the drum. Each fabric member in being carried around 120 the drum by the guide 17 is, at the same time, carried forward a distance equal to its own length, so that when it is a second time presented to the drum it has been moved toward the outer end of the drum sufficiently 125 to bring its loops 115 into position to receive the wire 103 which is to form a new fabric member. Thus the continued operation of the machine results in the formation of a tubular link mesh fabric composed 130

of connected spiral convolutions of serially arranged fabric units. The series connections of adjacent units are provided by the hook-portions of units of the adjacent preceding convolution, said hook portions also serving to connect adjacent convolutions laterally.

It will be manifest that my invention is not confined to the specific process herein described, nor is it limited for use in connection with the specific machine set forth above, both the process and the means for carrying it out being capable of being modified considerably to suit individual requirements, without sacrifice of efficiency. The scope of the invention, therefore, is in no sense limited by the specific details of operation described herein, but must be determined by referring to the appended claims.

20 I claim—

1. The improved method of making tubular wire fabrics composed of spiral convolutions of connected, identical fabric units which interlock with the units of adjacent convolutions, which consists in severing equal lengths of wire from a continuous wire supply, forming these lengths of wire into fabric units and interlocking said fabric units with the similar units of a previously completed portion of said tubular fabric.

2. The improved method of making rectangular mesh bed spring fabric composed of parallel rows of similarly formed fabric units, which consists in severing equal lengths of wire from a continuous wire supply, forming these lengths of wire into fabric units and attaching said fabric units to each other to form spiral convolutions of a tubular mesh fabric, and laterally interlocking the rows of fabric units directly with each other to form rectangular mesh bed spring fabric.

3. The improved method of constructing rectangular-mesh tubular wire fabric made of wire units having limbs substantially parallel to the axis of the fabric, which consists in connecting one by one to the end of a previously completed fabric portion a circumferential series of wire fabric units having limbs arranged substantially parallel with the axis of the fabric and with the outer ends of said limbs disconnected, and thereby linking together the free ends of previously connected units whereby the inchoate rectangular meshes of said fabric are completed, one by one.

4. The improved method of making wire fabric formed of wire units, the limbs of which form boundaries of the meshes of the fabric, which consists in connecting to the end of a previously completed fabric portion a row of fabric units having limbs, the ends of which are free and project outwardly from their connections with the pre-

viously completed fabric portion and forming inchoate fabric meshes and thereby completing previously formed inchoate fabric meshes by connecting the outer free ends of the units of a previous row.

5. The improved method of making fabric formed of identical wire units, the limbs of which form boundaries of the meshes of the fabric, which consists in connecting to the end of a previously completed fabric portion the intermediate portions of a row of identical wire fabric units, each made of a single piece of wire, the terminal portions of which form a pair of limbs separated to constitute sides of an inchoate fabric mesh, the ends of said limbs being free and projecting outwardly from the end of the previously completed fabric portion and thereby completing previously formed inchoate meshes by connecting the outer free ends of the limbs of the units in the row previously connected to said fabric portion.

6. The improvement in the process of constructing mesh fabric from wire units, which consists in engaging the unit with the edge of a previously completed portion of said mesh fabric, and subsequently forming the unit to provide means for connecting a subsequent unit thereto.

7. The improvement in the process of constructing mesh fabric of wire units, which consists in engaging a portion of a unit with the edge of a previously completed portion of said mesh fabric, and subsequently forming another portion of the unit to provide means for connecting a subsequent unit thereto.

8. The improvement in the process of constructing wire mesh fabric composed of connected transverse rows of connected longitudinally disposed fabric units, which consists in engaging that portion of the wire member which is to become one edge of the unit with the end of a previously completed portion of said mesh fabric, and subsequently forming the unit to provide means for connecting a subsequent unit thereto.

9. The improvement in the process of constructing wire mesh fabric composed of connected transverse rows of connected longitudinally disposed fabric units, which consists in engaging that portion of the wire member which is to become one edge of the unit with the end of a previously completed portion of said mesh fabric, and subsequently forming an eye in said wire member whereby a subsequent unit may be connected thereto.

10. The improvement in the process of constructing wire mesh fabric composed of interconnected fabric units, which consists in engaging a wire member with the edge of a previously completed portion of said mesh fabric, and subsequently bending said

member, said bending operation including the formation of an eye to provide connection means for a subsequent unit.

11. The improvement in the process of 5 constructing wire mesh fabric composed of connected transverse rows of connected longitudinally disposed fabric units, which consists in threading a wire length into an eye at the edge of a previously completed portion of said mesh fabric, and subsequently 10 bending said member to provide a hooked arm extending outwardly from the edge of the fabric.

12. The improvement in the process of 15 constructing wire mesh fabric, which consists in engaging the central portion of a length of wire with a previously completed portion of said mesh fabric, and subsequently bending said wire length to form a

pair of arms extending outwardly from the 20 edge of the fabric.

13. The improvement in the process of constructing wire mesh fabric composed of transverse rows of fabric units, which consists in transversely moving a wire member 25 into engagement with the edge of a previously completed portion of said mesh fabric, and subsequently forming said wire member into the shape of a unit.

14. The improvement in the process of 30 constructing wire mesh fabric, which consists in threading the end of a length of wire through the eye of a unit on the edge of a previously completed portion of said mesh fabric, and subsequently forming an 35 eye on said end.

HARVEY E. BROWN.
